LINE SPACING DEVICE FOR TYPEWRITERS

Giuseppe Prezioso, Yverdon, Switzerland, assignor to E. Paillard & Cie S. A., a corporation of Switzerland

Application November 22, 1943, Serial No. 511,296
In Switzerland November 26, 1942

3 Claims. (Cl. 197—114)

In typewriters, calculating or like machines, the angular rotary displacements of the platen are generally operated by a lever actuated by hand when the end of the line is reached. This lever, pivoted on a part of the carriage, acts by the means of a pawl on a ratchet-wheel fixed to the platen. In these machines, the same lever operates the longitudinal displacement of the carriage at the same time as the angular displacement of the platen.

There are machines in which the movements of the carriage are operated by an electric motor. This latter acts then either by means of a tape passing over the front part of the machine onto the line-space and carriage-return lever, or onto a special lever fixed at the back of the machine, the hand-lever being then omitted.

The present invention refers to a device for controlling the movements of the platen and of the carriage of a machine, enabling these operations to be effected either by hand, by the usual line-space and carriage-return lever, or by mechanical means for instance by a motor through a lever placed at the back of the machine, the two levers acting on the same organs for the transmission of their movements.

The accompanying drawing shows diagrammatically an example of a form of execution of the control device.

Fig. 1 is a perspective view;

Fig. 2 is a view of a detailed part.

In Fig. 1, 10 represents the frame of the machine, for instance a typewriter, with carriage rails 11, for the carriage 12. The latter has at each end cases 13 which are provided with journal bearing for the platen 14. For greater clearness of the drawing the lid of case 13 is off. In this case 13 is mounted a support 15 on which is pivoted the first interline or space-line lever 16 of usual type for the manual controlling of the line-space and carriage-return. This lever 16 which is bent to form a bell crank acts on the platen 14 by means of a rod 17 articulated on one side, on its end 18 and, on the other side, on the end of a lever 19 which is loosely mounted on a pin 20 secured to case 13. A second lever 21 having a bent terminal lug 31 and a lateral finger 29, is loosely mounted on the pin 20, and at the end of this lever 21 is articulated a rod 22 connected by its other end with a ring 23 (Fig. 2) loosely mounted on the axis 24 of the platen 14. This ring 23 is provided with a pawl 25 subjected to the action of a spring 26. This pawl 25 engages a ratchet-wheel 27 secured to the shaft of platen 14.

The lever 19 is subjected to the action of a return-spring 28 causing it to rotate clockwise.

The rod 22 is subjected to the action of a return-spring 30 causing also lever 21 to rotate clockwise. This lever 21 is provided with the abutment 31 which engages lever 19, as well as another abutment 29.

Another lever 32 loosely mounted on the axis 20 is provided, which is subjected to the action of a return-spring 33 causing it to turn clockwise. At the end of the lever 32 is articulated a rod 34 connected to a lever 35 secured on a stub shaft 36 which latter is rotatably mounted in the frame of the carriage 12 and at the end of which is secured the second interline or space-line lever 37 for the mechanical or automatic controlling or rotation of the platen, for instance by means of a motor, of a pedal or other means not shown.

The lever 32 is so disposed as to be displaced 20 in the path of the abutment 29 of lever 21 with which it is normally in contact as shown in Fig. 1. Its spring 33 is meant to keep it in the position shown in the drawing, when the abutment 29 is displaced under the action of lever 16.

The abutment 31 of lever 21 is so disposed that 25 when the first interline lever 16 is pushed manually in the direction of the arrow A, it causes the lever 19 to rotate in an anti-clockwise direction and to carry lever 21 in the same movement by means of the abutment 31.

The abutment 29 of lever 21 causes also the 30 rotation of this lever in an anti-clockwise direction, when the lever 37 is pushed in the direction of the arrow B. In this case, the lever 19 and consequently first manual lever 16 remain still.

On the other hand, when the first manual lever 16 is pushed, the levers 32 and consequently 31 remain still.

In either of these two events, the operation of 40 pawl 25 which controls the driving of the platen 14 takes place by the same elements 17, 19, 21, 22, 23 which constitute a parallelogram.

38 is an abutment limiting the displacement 45 of the space-line pawl 25.

As clearly shown by the foregoing description, the two interline or space-line levers 16 and 37 for the manual and the mechanical actuation of the interline act independently from one another upon the same group of organs of command.

One can naturally provide also another mechanism of transmission than the one described and constituted by a parallelogram of levers.

It is obvious that in order to allow also the return of the carriage otherwise than manually, for instance by a motor acting on lever 37, the

latter can be connected by a tape 39 to an operating device subjected to the action of the motor.

Instead of pivoting the lever 37 on the rear side of the carriage 12, as shown in the drawing, this lever 37 could also pivot on another part of the latter, for instance on the top or on the lateral side.

I claim:

1. A device for the controlling and actuating of the movements of the platen of a typewriter or like machine, the moving part bearing the platen having two interline levers, for line-spacing the platen, one being operated manually, the other one being operated mechanically, the movements of these two levers being transmitted to the platen by one and same mechanical means, which is composed by levers forming a parallelogram having two opposite sides, one of which transmits the manual control only, and the other of which transmits either manual or mechanical control to the platen.

2. In a manually or automatically actuatable line spacer for a power operable writing machine, a platen, a platen ratchet, a platen pawl, mounting means carried by said platen for displaceably

mounting said platen pawl engageably with said platen ratchet, first rod means connected to said mounting means, an actuating lever pivotally connected to said first rod means and having a pair of projecting fingers, pin means for pivotally mounting said actuating lever, a manually operable handle, second rod means connected to said manually operable handle, a first auxiliary lever and a second auxiliary lever pivotally mounted on said pin means, respectively engageably with said projecting fingers, said first auxiliary lever being pivotally connected to said second rod means, and mechanically actuatable means connected for actuating said second auxiliary lever, said levers being so arranged that either auxiliary lever can be independently actuated to displace said actuating lever in the same direction of movement without affecting the other said auxiliary lever.

3. A line spacer according to claim 2, said rod means and levers being so mounted that in their normal operation said rod means respectively constitute opposite parallel sides of a parallelogram of which one other side is constituted of said actuating lever and said first auxiliary lever.

GIUSEPPE PREZIOSO.
